UNITED STATES PATENT OFFICE.

FREDERICK RICHARD SIMMS, OF KILBURN, ENGLAND, ASSIGNOR TO THE SIMMS MAGNETO COMPANY, OF BLOOMFIELD, NEW JERSEY, A CORPORATION OF NEW YORK.

MAGNETO-ELECTRIC MACHINE.

1,155,521.

Specification of Letters Patent.

Patented Oct. 5, 1915.

Application filed February 21, 1912. Serial No. 679,044.

To all whom it may concern:

Be it known that I, FREDERICK RICHARD SIMMS, a subject of the King of Great Britain, residing at Welbeck Works, Kilburn, Middlesex, England, have invented new and useful Improvements in Magneto-Electric Machines, of which the following is a specification.

My invention relates to improvements in combined ignition and illuminating devices for use on motor road vehicles, and to that class of appliance or installation in which the current for both lighting and ignition is obtained from a magneto-electric machine.

According to my invention I make use of a magneto-electric machine having two pairs of pole-pieces, between one pair of which there rotates a laminated armature for generating the lighting current and between the other pair of which there is arranged a Siemen's armature for generating the ignition current.

In practice I find it advantageous to make use of a permanent magnet which is built up of three separate magnets arranged side by side, the center magnet being longer than the two outside magnets and carrying the pole-pieces for the ignition armature, while the two outer or shorter magnets carry pole-pieces between which rotates the armature for generating the lighting current.

To enable the invention to be fully understood, I will describe it by reference to the accompanying drawings, in which:

Figure 1 is a sectional side elevation of a magneto-electric machine adapted for combined ignition and illuminating purposes according to the invention. Fig. 2 is a section on the line 2—2, Fig. 1, Fig. 3 is a section on the line 3—3, Fig. 1, Fig. 4 is a side view of the magnet.

The apparatus illustrated in Figs. 1 to 4 is of the kind in which three-horse-shoe-shaped magnets are arranged side by side. The two outside magnets are composed of three curved strips *a*, *b* and *c* and are secured at their ends to the upper pole-pieces *d*, *d* between which there rotates the armature *e* which is of the laminated type and is designed for generating the lighting current.

The center magnet is also composed of three curved or horse-shoe-shaped strips *f*, *g* and *h*, the lowermost of these strips *f* being extended downward and carrying the lower pole-pieces *i*, *i* between which there rotates

a Siemen's armature *j*, for generating the ignition current, the two upper strips extending, similarly to the sections *b* and *c* of the outside magnets, to the upper pole-pieces *d*, *d* to which they are similarly secured. 60

The armature *j* is driven from the spindle *j*¹ in the usual manner and the armature *e* is driven from the said spindle through the medium of the toothed gears *k*, *k*¹.

It will be understood from the foregoing 65 description that when the magneto-electric machine is driven in the usual way from the engine a current is generated in each of the two armatures *e* and *j*, the current from the armature *e* being distributed and used for 70 lighting purposes, and that from the armature *j* being distributed to the sparking plugs of the engine cylinders for ignition purposes in the usual manner.

Claims:

1. In a magneto electric machine for generating separate currents for ignition and lighting circuits, the combination with a plurality of permanent horse shoe magnets having their arms extending in the same direction, the arms of certain of said magnets being extended beyond the arms of the others, a pair of pole shoes secured to said extended arms, an armature located between said pole shoes, a pair of pole shoes secured 80 to the shorter magnet arms, and a separate armature located between said pole shoes. 85

2. In a magneto electric machine for generating separate currents for ignition and lighting circuits respectively, the combination with a plurality of permanent horse shoe magnets located side by side, and having their arms extending in the same direction, one of said magnets being provided with arms extending beyond those of the other magnet or magnets, a pair of pole shoes secured to said extended arms, an armature located between said pole shoes, a pair of pole shoes secured to the shorter magnet arms and a separate armature located between said pole shoes. 95

3. In a magneto electric machine for generating separate currents for ignition and lighting circuits respectively, the combination with a plurality of permanent magnets, arranged side by side, each comprising a plurality of superimposed horse shoe shaped strips, having their arms extending in the same direction, the arms of certain of said strips being extended beyond the others, a 100

pair of pole shoes connected to said extended arms, a pair of pole shoes connected to the arms not so extended, and separate and differentially constructed armatures located 5 between said pairs of pole shoes respectively.

4. In a magneto electric machine for generating separate currents for ignition and lighting circuits respectively, the combination with a plurality of permanent magnets, 10 arranged side by side, each comprising a plurality of superimposed horse shoe shaped strips, having their arms extending in the same direction, the arms of certain of said strips being extended beyond the others, a pair of pole shoes connected to said extended arms, a pair of pole shoes connected to the arms not so extended, and an independent armature located between each of said pairs 15 of pole shoes.

5. In a magneto electric machine for generating separate currents for ignition and lighting circuits respectively, the combination with a central permanent magnet comprising 20 a plurality of superimposed horse shoe shaped strips, the arms of one of said strips being extended beyond those of the others, and permanent magnets located on opposite sides of said central magnet, each composed of a plurality of horse shoe shaped strips having arms substantially of the 25 length of the short arms of said central magnet, all of said arms extending in the same direction, a pair of pole shoes secured to said extended arms, an armature located between said pole shoes, a pair of pole shoes secured to the arms of the end magnets and the short arms of said central magnet, and a separate armature located between said pole shoes.

40 6. In a magneto electric machine for producing separate currents for ignition and lighting circuits respectively, the combina-

tion with a permanent magnet comprising a plurality of superimposed horse shoe shaped strips, one of which is provided with arms 45 extended beyond the others, and a separate permanent magnet arranged beside the first mentioned magnet, and comprising a plurality of horse shoe shaped strips having their arms of substantially the same length 50 as the shorter arms of the first mentioned magnet, a pair of pole shoes secured to said extended arms, an armature constructed to generate an ignition current located between said shoes, a separate pair of pole shoes connected to all of said shorter arms, and an armature constructed to generate a lighting current located between said pole shoes.

7. In a magneto electric machine for producing separate currents for ignition and 60 lighting circuits respectively, the combination with a centrally located permanent magnet comprising an inner horse shoe shaped strip having its arms extended and two outer horse shoe shaped superimposed strips 65 having shorter arms, and a pair of permanent magnets located on opposite sides of the central magnet and comprising three horse shoe shaped strips having arms of substantially the same length as the shorter 70 arms of the central magnet, a pair of pole shoes secured to the extended arms of the central magnet, an armature constructed to generate ignition current located between said pole shoes, a separate pair of pole shoes secured to the arms of the end magnets and the shorter arms of the central magnet, and an armature constructed to generate lighting 75 current located between said pole shoes.
